UNITED STATES PATENT OFFICE.

DANIEL LEE, OF SACRAMENTO, ASSIGNOR TO WILLIAM GOULD, OF SAN FRANCISCO, CALIFORNIA.

FEED-WATER HEATER.

SPECIFICATION forming part of Letters Patent No. 331,307, dated December 1, 1885.

Application filed July 31, 1885. Serial No. 173,182. (No model.)

To all whom it may concern:

Be it known that I, DANIEL LEE, a citizen of the United States, residing at Sacramento, in the county of Sacramento and State 5 of California, have invented a new and useful Feed-Water Heater and Sediment-Collector for Steam-Boilers, of which the following is a specification.

The objects of my invention are to provide a means whereby the water-supply of steam-boilers is heated in a separate tank-connection with the boiler and quickly brought to such a degree of heat that the sediment—such as lime, mud, and other impurities—15 will be precipitated and collected in the tank, and not be permitted to enter the boiler and be converted into scale. I accomplish these objects by the means illustrated in the accompanying drawing, in which the figure is a side 20 sectional elevation of my feed-water heater and sediment-collector.

In carrying out my invention I employ a tank, A, of any desired shape or dimensions, and place it over the shell of the boiler at a 25 point a little to the rear of the transverse center line thereof, and mounted upon suitable supports, B. The tank is constructed air and water tight, so that it can be operated under pressure, and a cover, C, is suitably 30 clamped to the top portion thereof, for the purpose of cleansing the interior when necessary. Through the cover is introduced a pipe, C', to which is connected a cock, C', used as a vent or blow-off cock should the 35 tank become overcharged with steam or compressed air. The interior of the tank is divided centrally by a vertical diaphragm, D. The upper and lower ends of the diaphragm do not connect with the ends of the tank, but 40 a small space is left open at both ends for the free circulation of steam and water in the ends of the tank from one compartment to the other, as shown. The steam-boiler E is pierced at E' to receive the steam-pipe F 45 and the feed-water pipe G. The steam-pipe is placed above the water-line and the feed-water pipe below the water-line in the boiler, and the feed-pipe G is provided with a rectangular extension, the end of which is per-

forated with holes G', while the steam-pipe 50 F is provided with a right-angle extension, also perforated at F'. The steam-pipe F connects with the tank near the top, while the feed-pipe G connects with the tank lower down, or just beneath the center line, and 55 both are provided with suitable cocks, H. A cold-water-feeding pipe, I, connects with the pump or source of supply and enters the tank a little below the upper end, and the end of this pipe is also pierced with holes or 60 provided with a rose-jet, J. The perforations at the ends of these pipes are made for the purpose of a more gradual introduction of the heated water to the boiler through its pipe and prevent a too rapid and great a 65 rush of steam through the steam-pipe into the tank from the boiler, while the perforations in the end of the cold-water-feed pipe will arrest the coarser particles of sediment in the cold water from entering the tank. The side 70 of the tank is pierced just above the bottom plate to receive a blow-off pipe, R, whereby the sediment collected or precipitated can be blown off and out into the sewer or washed out with water from the cold-water- 75 feed pipe by shutting off the hot-water-feed pipe leading into the boiler. Both of these pipes—the cold-water feed and blow-off pipe—are provided with suitable cocks, as shown.

In operation the cold water is admitted to the tank through the cold-water feed or supply pipe I, which fills the tank to a sufficient height, when steam is admitted through the pipe F, connecting with the boiler. 85 This soon heats up the contents of the tank, causing a circulation of the steam and water above and below the ends of the diaphragm in the directions shown by the arrows, and precipitating the sediment to the bottom of 90 the tank to be blown off through the waste-pipe into the sewer.

Having thus described my invention, what I claim, and desire to secure by Letters Patent, is—

In a feed-water heater, the combination of a steam-tank, J, provided with a central vertical diaphragm, D, a hot-water-feed pipe,

G, entering the boiler below the water-line and having a perforated end, a steam-pipe, F, entering the boiler above the water-line and having also a perforated end, the cold-water-supply pipe I, and the blow-off pipe R, all constructed, arranged, and operating substantially as shown and described.

In testimony that I claim the foregoing I have hereunto set my hand and seal.

DANIEL LEE. [L. s.]
